UNITED STATES PATENT OFFICE.

HENRY H. HESS AND JOSEPH F. PARKER, OF MOBILE, ALABAMA, ASSIGNEES TO PAUL P. LOCKLING IMPROVED AUTOMATIC PASSENGER FARE REGISTERING COMPANY, OF MOBILE, ALABAMA, A COPARTNERSHIP.

APPARATUS FOR PRINTING AND DELIVERING TRANSFER-SLIPS.

1,113,783.

Specification of Letters Patent. Patented Oct. 13, 1914.

Application filed January 16, 1914. Serial No. 812,528.

To all whom it may concern:

Be it known that we, HENRY H. HESS and JOSEPH F. PARKER, citizens of the United States, residing at Mobile, in the county of 5 Mobile and State of Alabama, have invented certain new and useful Improvements in Apparatus for Printing and Delivering Transfer-Slips; and we do hereby declare the following to be a full, clear, and exact 10 description of the invention, such as will enable others skilled in the art to which it appertains to make and use the same.

Our present invention relates to improvements in apparatus for printing and delivering transfer slips, such as are given from railway cars, busses, or the like.

The invention is intended to provide apparatus for printing the name of the street for which the transfer is given, the time at 20 which the transfer is given, and also for printing the conductor's number, the name of the street or line issuing the transfer, the month and day of the month, and A. M. or P. M., interchangeable according to time of 25 day, and any advertising or descriptive matter that it is desired to print on the back of the transfer slip.

The invention consists in certain novel features that will be hereinafter described 30 and claimed.

Reference is had to the accompanying drawings, in which similar parts are indicated by similar reference symbols throughout the several views.

Figure 1 shows a vertical section along the line 1—1 of Fig. 3, and looking in the direction of the arrows; Fig. 2 shows a plan view of the apparatus; Fig. 3 shows a section along the line 3—3 of Fig. 1 and looking 40 down, parts being shown in elevation; Fig. 4 shows the operating lever and the ratchet wheel operated thereby, with the contiguous parts; Fig. 5 is a detail showing the thumb wheel for turning the printing roller by 45 hand, with the stop for locking the printing roller in the desired position; Fig. 6 is a detail showing the indicating disk used for indicating the total number of transfers registered and Fig. 7 shows the front of one 50 of the printed slips as turned out from the machine.

Referring especially to Figs. 1, 2 and 3, A represents a casing which is in the form of a box having one open side, closed by the door

A' hinged, as at a , to the body portion of the 55 box. The door is locked in place in any convenient way. We provide a frame bearing the mechanism which is adapted to slide into this box A when the door is open, the said frame comprising two side plates B 60 and the transverse webs B' supporting the plate B', as shown in Fig. 1. Connecting these side plates B are a series of rods or arbors serving as bearings for the various wheels which will be hereinafter described. 65 These rods and arbors serve to stiffen the frame. The spindle C is journaled between the plates B and carries the drum C' on which is wound the paper roll C'; the strip of paper of which is led over the idler C' 70 and above the plate B' and through the slot a' in the end of the box, as shown in Fig. 1. An endless printing ribbon D is mounted over the feed roller E and over the idlers E', 75 E² and E³, and passes between the plate B', the printing roll F and the printing block H', as shown in Fig. 1. The printing roller F is mounted on the shaft F', which is normally pressed upward by the springs h², the lower ends of which springs engage in suitable 80 bearings in the frame B. The periphery of the printing roller F is provided with a series of flattened faces f, on which is placed raised type indicating the names of the streets, as Ohio, Wis., Utah, etc., as 85 shown in Fig. 3. These represent the junctions at which transfers are issued. The top of the casing is preferably provided with corresponding indicia, as shown at a^2 in Fig. 2. The printing roller F may be set to print the desired junction either by turning the thumb wheel F², see Figs. 2, 3 and 5, which thumb wheel is notched, as at f², to engage the catch f³, which catch serves to hold the printing wheel F in the desired angular 95 position, and yet will permit the same to be turned by hand as already stated; or by means of the rack G which is connected to the handle G' and carries a pointer g, see Fig. 2, which pointer may be moved to the 100 desired indication of junction shown on the top of the box A. The shaft F' projects the heel H² of the housing H, which carries the clock mechanism H', the hour and minute hands of which travel over 105 the bottom of a disk above the ribbon D. These hour and minute hands are shown in dotted lines in Figs. 2 and 3, as also the

name of issuing line, A. M., or P. M., date, and conductor's number. This housing H carries a rod H^o, the ends of which engage the springs h' mounted in the side plates B on the frame. When the housing H is pressed downward, against the action of the springs h', as will be hereinafter described, it will be obvious that the printing roller F and the time indicating hands will be pressed 5 downward against the ribbon D making an imprint on the paper slip passing between said ribbon and the plate B'. The pressing down of this housing H may be conveniently accomplished by means of the operating lever I, which is preferably bent out, as at i, to clear the thumb wheel F², and is secured to the end of the operating shaft I', which operating shaft has secured thereon an eccentric I², and swinging the lever I 10 downward will cause the eccentric to cam down the housing H and operate the printing roller and time indicator as stated. The movement of the operating lever also sets in operation the feed mechanism which will 15 now be described. This feed mechanism comprises a sleeve J, having an arm J', which sleeve is loosely mounted on the shaft I', and is provided with the shoulder j so as to permit of the desired amount of lost motion of the shaft I' relative to said sleeve before said arm J' is rocked. This lost motion is desirable so as to permit a long swing of the operating lever I and a short angular movement of the arm J', which would otherwise 20 strike the top of the casing. This arm J' is connected by the link J² to the yoke J³, which yoke straddles the ratchet wheel K and carries a pawl J⁴ adapted to engage the teeth of said ratchet wheel. The spring J⁵, 25 normally under tension, tends to restore the operating lever to the initial position and to feed the ratchet wheel forward one tooth when the operating lever is released. The ratchet wheel K is fast on the spindle K', 30 which carries the pinion K² meshing with the gear wheel L, which in turn meshes with the pinion E⁴ fast on the same shaft E^o as the ribbon feed wheel E. Thus when the ratchet wheel K is fed forward, this ribbon 35 D will be fed forward also. Mounted on the same shaft K' with the ratchet wheel K is a gear wheel K³ which meshes with the pinion M on the same shaft with the gear wheel M' which latter meshes with the pinion N on 40 the same shaft with the secondary printing roller N'. The paper strip e is pressed against this secondary printing roller N' by means of the roller P, whose shaft P' is pressed downward by the springs P². For 45 convenience of assembly, the ends of this shaft P' are mounted in slots b' in the side plates B of the frame. This secondary printing roller N' is inked in any convenient way, as by means of the inking roller Q 50 mounted on the shaft Q', which shaft is

pressed upward by the springs Q². The ends of this shaft Q' for convenience of assembly are preferably mounted in slots b' in the plates B of the frame, as shown in Fig. 1. This secondary printing roller N' may be provided on its periphery with any suitable type to indicate any instructions to be given to the passenger, or any advertising matter, or any other matter which it is desired to print on the back of the transfer slip. It 70 will be noted that the imprint from the roller F and the time indicator H will be on one side of the strip, while the imprint from the roller N' will be on the other side, or back of the strip. 75

In order to indicate the number of transfer slips that are fed from the machine, we provide suitable indicating apparatus, such as shown in detail in Fig. 6, in which K⁴ represents a disk secured on the end of the shaft K', and which disk is provided with a lug k adapted to engage in the notches r of the indicating wheel R. This indicating wheel R is shown as calibrated to show sixteen operations of the machine for each notch of the wheel, so that every time the disk K⁴ pushes this wheel R around one notch, sixteen transfer slips will have been given out. It will be obvious that the parts may be arranged and the apparatus calibrated to any 90 desired series of units, such as the decimal system, or the like. The indicating wheels are so fitted with frictional devices, that they may be set at the zero or starting point. 95

One object of this invention is to require 100 the conductor to give each passenger a transfer slip when he gets on the car, whether he wishes a transfer or not. If he does not wish the transfer he can destroy it, or he may read the advertising matter printed by the 105 wheel N'. If the passenger does not desire to use the transfer, it is simply left blank, no transfer line being indicated. If, however, he wishes a transfer at some junction the conductor moves the handle G' until the 110 pointer g points to the desired junction, which will cause the rack L to rotate the printing wheel F to the proper position and then by operating the hand lever I the junction and the time the transfer is given will 115 be both printed. When the operating lever is let go, the spring J⁵ will restore the operating lever to the initial position, releasing the eccentric I² from engaging with the housing H and permitting the spring h' to lift 120 the wheel F and the time indicator H clear of the ribbon D. At the same time that this spring is restoring the operating lever to the initial position, it is causing the pawl J⁴ to rotate the ratchet wheel K, one tooth operating the ribbon feed roller E and the secondary printing roller N', thus feeding the ribbon in the desired direction, and also simultaneously feeding the strip forward. 125 The strip projecting from the end of the slot 130

a^o is readily torn off and handed to the passenger. When so presented, this strip will have the junction for which the transfer is desired and the time the transfer is given printed on one side, and the advertising matter, or other matter, printed by the roller N' impressed on the other side.

5 By requiring the conductor to give to each passenger a transfer slip when he pays a cash fare, whether he asks for it or not, the total number of persons entering the car who pay cash fares would be indicated on the indicator R.

10 It will be obvious that various modifications might be made in the herein described apparatus, and in the construction, combination and arrangement of parts which could be used without departing from the spirit of our invention.

20 Having thus described our invention, what we claim and desire to secure by Letters Patent of the United States is:—

1. In an apparatus of the character described, the combination with a casing of 25 means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for pressing said housing downward toward said ribbon, means for automatically returning said housing to the initial position when released, 30 and spring operated feed mechanism automatically operated upon the release of said lever for feeding said paper strip and said printing ribbon, substantially as described.

2. In an apparatus of the character described, the combination with a casing of 40 means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for pressing said housing downward toward said ribbon, means for automatically returning said housing to the initial position when released, 45 and spring operated feed mechanism automatically operated upon the release of said lever for feeding said paper strip and said printing ribbon, with means for setting said printing wheel at the desired position, substantially as described.

3. In an apparatus of the character described, the combination with a casing of 50 means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for press-

ing said housing downward toward said ribbon, means for automatically returning said housing to the initial position when released, 55 and spring operated feed mechanism automatically operated upon the release of said lever for feeding said paper strip and said printing ribbon, with a secondary printing roller adapted to make an impression on the paper strip on the opposite side thereof from that made by the printing wheel and housing aforesaid, with means operated by said feed mechanism for rotating said secondary printing roller, substantially as described.

4. In an apparatus of the character described, the combination with a casing of 60 means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for pressing said housing downward toward said ribbon, means for automatically returning said housing to the initial position when released, 65 and spring operated feed mechanism automatically operated upon the release of said lever for feeding said paper strip and said printing ribbon, with means for setting said printing wheel at the desired position, with a secondary printing roller adapted to make an impression on the paper strip on the opposite side thereof from that made by the printing wheel and housing aforesaid, with means operated by said feed mechanism for 70 rotating said secondary printing roller, substantially as described.

5. In an apparatus of the character described, the combination with a casing of 75 means for carrying a paper strip mounted therein, a housing carrying clock mechanism with clock hands mounted in said casing, a printing wheel journaled in said housing, a printing ribbon mounted between said paper strip and said housing, a hand lever, a cam operated by said hand lever for pressing said housing downward toward said ribbon, springs for automatically returning said housing to the initial position when released, means for automatically restoring said hand lever to the initial position when released, and feed mechanism automatically operated upon the release of said lever for feeding said paper strip and said printing ribbon, substantially as described.

6. In an apparatus of the character described, the combination with a casing of 80 means for carrying a paper strip mounted therein, a housing carrying clock mechanism with clock hands mounted in said casing, a printing wheel journaled in said housing, a printing ribbon mounted between said paper strip and said housing, a hand lever, a cam operated by said hand lever for pressing said housing downward toward said ribbon,

springs for automatically returning said housing to the initial position when released, means for automatically restoring said hand lever to the initial position when released, 5 and feed mechanism automatically operated upon the release of said lever for feeding said paper strip and said printing ribbon, with means for setting said printing wheel at the desired position, substantially as described. 10

7. In an apparatus of the character described, the combination with a casing of means for carrying a paper strip mounted therein, a housing mounted in said casing, 15 a printing wheel journaled in said housing, a printing ribbon mounted between said paper strip and said housing, a hand lever, means operated by said hand lever for pressing said housing downward toward said ribbon, means for automatically returning said housing to the initial position when released, 20 and spring operated feed mechanism automatically operated upon the release of said lever for feeding said paper strip and said printing ribbon, with a secondary printing roller adapted to make an impression on the paper strip on the opposite side thereof from that made by the printing wheel aforesaid, with means operated by said feed 25 mechanism for rotating said secondary printing roller, substantially as described. 30

8. In an apparatus of the character described, the combination with a casing of means for carrying a paper strip mounted therein, a housing mounted in said casing, a printing wheel journaled in said housing, a printing ribbon mounted between said paper strip and said housing, a hand lever, means operated by said hand lever for 35 pressing said housing downward toward said ribbon, springs for automatically returning said housing to the initial position when released, and spring operated feed mechanism automatically operated upon the 40 release of said lever for feeding said paper strip and said printing ribbon, with means for setting said printing wheel at the desired position, with a secondary printing roller adapted to make an impression on the 45 paper strip on the opposite side thereof from that made by the printing wheel and housing aforesaid, with means operated by said feed mechanism for rotating said secondary printing roller, substantially as described. 50

9. In an apparatus of the character described, the combination with a casing of means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for pressing 60 said housing downward toward said ribbon, 65

bon, means for automatically returning said housing to the initial position when released, and feed mechanism automatically operated upon the release of said lever for feeding said paper strip and said printing ribbon, comprising a ratchet wheel, a pawl released by said hand lever incident to the downward movement of said housing, a spring pulling said pawl in the reverse direction when released by said hand lever, and gearing driven 70 by said ratchet wheel under the action of said spring, substantially as described. 75

10. In an apparatus of the character described, the combination with a casing of means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for pressing said housing downward toward said ribbon, means for automatically returning said housing to the initial position when released and feed mechanism automatically operated upon the 80 release of said lever for feeding said paper strip and said printing ribbon, comprising a ratchet wheel, a pawl released by said hand lever incident to the downward movement of said housing, a spring pulling said pawl in the reverse direction when released by said hand lever, and gearing driven by said ratchet wheel under the action of said spring, with means for setting said printing wheel at the desired position, substantially as described. 85 90

11. In an apparatus of the character described, the combination with a casing of means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for pressing said housing downward toward said ribbon, means for automatically returning said housing to the initial position when released, and feed mechanism automatically operated upon the release of said lever for feeding said paper 105 strip and said printing ribbon, comprising a ratchet wheel, a pawl released by said hand lever incident to the downward movement of said housing, a spring pulling said pawl in the reverse direction when released by said hand lever, and gearing driven by said ratchet wheel under the action of said spring, with a secondary printing roller adapted to make an impression on the paper strip on the opposite side thereof from that made by the printing wheel and housing aforesaid, with means operated by said feed mechanism for rotating said secondary printing roller, substantially as described. 110 115

12. In an apparatus of the character de- 130

scribed, the combination with a casing of means for carrying a paper strip mounted therein, a housing carrying clock mechanism with clock hands mounted in said casing, a printing wheel journaled in said housing, a printing ribbon mounted between said paper strip and said housing, a hand lever, means operated by said hand lever for pressing said housing downward toward said ribbon, means for automatically returning said housing to the initial position when released, and feed mechanism automatically operated upon the release of said lever for feeding said paper strip and said printing ribbon, comprising a ratchet wheel, a pawl released by said hand lever incident to the downward movement of said housing, a spring pulling said pawl in the reverse direction when re-

leased by said hand lever, and gearing driven by said ratchet wheel under the action of said spring, with means for setting said printing wheel at the desired position, with a secondary printing roller adapted to make an impression on the paper strip on the opposite side thereof from that made by the printing wheel and housing aforesaid, with means operated by said feed mechanism for rotating said secondary printing roller, substantially as described. 20

In testimony whereof, we affix our signatures, in presence of two witnesses. 30
